DESIGN.

F. A. SEIFERT,

HEATING STOVE.

No. 17,575.

Patented Aug. 2, 1887.

UNITED STATES PATENT OFFICE.

FRANK A. SEIFERT, OF ST. LOUIS, MISSOURI.

DESIGN FOR A HEATING-STOVE.

SPECIFICATION forming part of Design No. 17,575, dated August 2, 1887.

Application filed June 21, 1887. Serial No. 242,050. Term of patent 14 years.

To all whom it may concern:

Be it known that I, FRANK A. SEIFERT, a citizen of the United States, residing at the city of St. Louis, Missouri, have invented and 5 produced a new and original Design for Heating-Stoves, of which the following is a specification, reference being had to the annexed engraving, forming part thereof, and showing the newly-designed stove in perspective.

10 The body a of the stove A is an oval prism, having projections a' a^2 at its ends, respectively, beneath one of which is a hearth, a^3 . The body rests upon an oval base-plate, a^4 , which in turn rests upon the legs a^5 . A 15 crowned oval top plate rests upon and overhangs the stove-body, and upon the top plate is an urn, a^6 , having a tulip-shaped finial, a^7 .

The leading feature of the design is the diaper-work B upon the front of the stove, in combination with the chrysanthemum ornamentation C upon the ends and top of the stove. The diaper-work extends across the upper portion of the stove-front above the register a^8 , and at each side of it appears vertical strap-work D . The chrysanthemum is shown in the form of a spray upon the projection a^2 , in the form of a cluster above the projection a^2 , and in the form of sprigs arranged as a wreath around the urn upon the top plate. Upon the 25 legs a^5 are horizontal ribs E , and beneath is a single chrysanthemum-blossom.

I claim—

1. The design for a heating-stove herein shown and described, the same consisting of

the oval body having the end projections resting upon a base-plate, and having a crowned oval top plate surmounted by an urn, the whole having the ornamentation shown. 35

2. In a design for a heating-stove, the stove-front bearing the ornamentation consisting of 40 the diaper-work and vertical strap-work, as shown.

3. In a design for a heating-stove, the stove-body provided above its end projection with ornamentation consisting of the cluster of 45 chrysanthemums, as shown.

4. In a design for a heating-stove, the top plate provided with ornamentation consisting of the sprigs of chrysanthemums arranged as a wreath around the urn, as shown. 50

5. In a design for a heating-stove, the stove-legs provided with ornamentation, consisting of the horizontal ribs and the chrysanthemum-blossom, as shown.

6. In a design for a heating-stove, the stove-front and top provided with the ornamentation consisting of the diaper-work and the chrysanthemums, as shown. 55

7. In a design for a heating stove, the design herein shown and described, the same consisting of the diaper-work upon the stove-front, in combination with the chrysanthemum ornamentation upon the ends and top of the stove. 60

FRANK A. SEIFERT.
